US0D1078239S

(12) United States Design Patent (10) Patent No.: US D1,078,239 S
(45) Date of Patent:  Jun. 10, 2025

(54) SHOE

(71) Applicant: Wang Haosen, Quanzhou (CN)

(72) Inventor: Wang Haosen, Quanzhou (CN)

() Term: 15 Years

(21) Appl. No.: 29/988,611

(22) Filed: Feb. 5, 2025

(51) LOC (15) Cl. 02-04

(52) U.S. Cl.

USPC D2/916

(58) Field of Classification Search

USPC D2/916, 919-926, 932-946, 961,
D2/969-978

(57) CLAIM

The ornamental design for a shoe, as shown and described.

DESCRIPTION

FIG. 1 is a top view of a shoe;

FIG. 2 is a bottom view thereof;

FIG. 3 is a front view thereof;

FIG. 4 is a rear side view thereof;

FIG. 5 is a right side view thereof;

FIG. 6 is a left side thereof;

FIG. 7 is a perspective view thereof; and,

FIG. 8 is a perspective view thereof in an unsecured configuration.

The broken lines depicting the sole on the bottom of the shoe in FIG. 2 form no part of the claim. The broken lines depicting a region on the unsecured portions of the shoe in FIG. 8 form no part of the claim. The broken lines depicting regions on the secured portions of the shoe in FIGS. 4 and 5 form no part of the claim.

1 Claim, 8 Drawing Sheets
